UNITED STATES PATENT OFFICE.

GEORGE VAN ZANDT, OF OAK PARK, ILLINOIS.

HAND-STAMP.

SPECIFICATION forming part of Letters Patent No. 288,385, dated November 13, 1883.

Application filed November 22, 1881. (No model.)

To all whom it may concern:

Be it known that I, GEORGE VAN ZANDT, a citizen of the United States, residing at Oak Park, in the county of Cook and State of Illinois, have invented a new and useful Hand-Stamp, of which the following is a specification.

My invention relates to hand-stamps in which the die-plate oscillates and inks itself upon a cloth cushion.

The objects of my improvement are, first, to simplify and cheapen the construction; second, to permit the die-plate to adjust itself upon the ink-pad; third, to prevent vibration of the die-plate when printing; fourth, to prevent noise or jarring in the movement; fifth, to provide an easy way of repairing; sixth, to arrange the stamp so that it may be separated and put together without tools; and, seventh, to provide in the die-plate a suitable fastener for removable type. I attain these objects by the stamp illustrated in the accompanying drawings, in which—

Figure 1 is a sectional view, with the die-plate in the position assumed when at rest against the ink-pad. Fig. 2 is a similar view, with the plate partly turned. Fig. 3 shows the plate inverted in the position assumed when printing. Fig. 4 is a sectional view at right angles to that shown in Fig. 1. In these four figures the die-plate shown is plain, not the style suited for removable type. Fig. 5 is a view of the plate used for removable dating-types. Fig. 6 shows one end of the die-plate. Fig. 7 is a sectional view lengthwise of the plate shown in Fig. 5.

Similar letters indicate similar parts in all the figures.

A is a hollow handle containing a spiral spring, which presses up against the handle and down on the end of the rod B, which is partly inserted. The rod is riveted to the frame D, which is a piece of metal cut and bent as shown, and having a long straight slot in each leg.

C is an elastic metal yoke attached to the handle A and inclosing the frame D, and having a short pin, F', riveted in each end.

E is the oscillating plate, rectangular in shape, and having at one end a part bent over for an ear or lug, Fig. 6, and at the other a

larger ear, in which is cut a peculiar slot, K; which acts as cam. In both ears are pivot-holes F, which allow the plate to turn on the pins F' that are inserted therein. One of these pins is riveted to each end of the yoke C, and passes through the slot H in the frame D.

G is a small rod, riveted at each end to the legs of the frame D, firmly bracing them. It is in the cam-slot K, and acts as a fulcrum to turn the plate.

K refers to the cam-slot, shaped as shown in Fig. 1. The sides are not parallel, but each has a curve peculiar to itself. It fits loosely over the fulcrum, except at and near its open end. It controls the movement of the die-plate oscillating upon the pivots in combination with the fulcrum attached to the frame having the long straight slot.

L refers to the ink-pad, suggested by the dotted lines.

O is a rectangular hole cut in the die-plate to fit it for removable dating-type. The metal in this hole is cut lengthwise in the center and each half struck up square.

P represents a metal arm pivoted at one end to the die-plate. It has a part struck up for a handle, S, and teeth T, passing through a slot, W, on one side of the opening O. The free end is bent to snap over and fasten upon a round rivet-head.

V refers to the metal struck up from the opening O on the side next to the teeth. Through it a narrow slot, W, is cut, and through the slot the teeth project into the opening. V' refers to the metal on the other side.

The action is as follows: The handle A, being pressed downward upon the stem B, carries the yoke C, having the pins F', and the die-plate, which is pivoted on the pins. As the pins follow the straight slot H the plate moves away from the ink-pad until the side of the slot K touches the fulcrum G. It touches lightly at first, then with gradually increasing pressure and speed it turns over the fulcrum, and the pressure and speed gradually diminish and the plate is inverted without shock or noise. A straighter part of the slot K then incloses the fulcrum G, touching it on both sides, steadyng the plate and guiding it perpendicularly to its work of printing. The

straight slot H is somewhat narrower at its lower end to perfect the bearing in this position. (See the bearing in Fig. 3.) When pressure is removed from the handle A, the 5 spring returns all parts to the position in Fig. 1.

The stamp may be separated by opening the elastic yoke C, and thereby drawing the pins out of the pivot-holes F.

The action of the part arranged for removable type is as follows: Pressure on the handle S will move the arm P in direction of the arrow, and the teeth are withdrawn through slot W releasing the type. New type being inserted, the arm P is pressed back into place, 15 and the teeth enter the opening and hold the type against the opposite side.

I am aware that prior to my invention self-inking stamps with removable type have been made and used, and I do not therefore claim 20 such a combination, broadly; but

What I do claim as my invention, and desire to secure by Letters Patent, is—

1. The plate E, oscillating upon the pins F', and having the cam-slot K, in combination with the frame D, having the slot H, and provided with the fulcrum G, all substantially as 25 set forth.

2. The elastic yoke C, having the short pins F', in combination with the frame D, having the slots H, and plate E, having pivot-holes 30 F, all substantially as shown.

3. The die-plate E, having projections V and V' and opening O, in combination with the arm P, provided with handle S, and teeth for engaging through slot W, with the removable type, all substantially as specified. 35

GEORGE VAN ZANDT.
